PALLET

Dennis M. Melnick and Mark Kubick, Baden, Pa.,
assignors to Pallet Development Inc., Ambridge, Pa.

Filed Aug. 24, 1972, Ser. No. 283,589

Term of patent 14 years

Int. Cl. D12—99

U.S. Cl. D14—3 N

Fig. 1

Fig. 2

FIG. 1 is an isometric view particularly showing the top construction of a pallet employing our new design; FIG. 2 is an isometric view on the same scale as FIG. 1 showing the bottom construction of the pallet.

Opposite ends and opposite sides of the pallet are identical.

We claim:

The ornamental design for a pallet, as shown and described.
